(57) **CLAIM**

I claim the ornamental design for a bicycle cable, as shown and described.

DESCRIPTION

FIG. 1 is a right, front, top perspective view of a bicycle cable showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a drawing showing the bicycle cable in use;

FIG. 9 is a left, front, bottom perspective view thereof;

FIG. 10 is a partially-enlarged front elevational view;

FIG. 11 is another drawing showing the bicycle cable in use; and,

FIG. 12 is a partially-enlarged view of FIG. 11.

The broken lines in the drawings illustrate portions of the bicycle cable which form no part of the claimed design. The dot-dashed lines in FIGS. 1 6, 7, 9, 10, 11 and 12 define the boundary of claimed and unclaimed objects, and the dot-dashed line forms no part of the claimed design.

1 Claim, 8 Drawing Sheets
